CLAIM

We claim the ornamental design for a folding-platform bicycle carrier, as shown and described.

DESCRIPTION

FIG. 1 is a perspective view of a folding-platform bicycle carrier;

FIG. 2 is a front elevational view thereof;

FIG. 3 is a rear elevational view thereof;

FIG. 4 is left side elevational view thereof;

FIG. 5 is a right side elevational view thereof;

FIG. 6 is a top plan view thereof; and

FIG. 7 is a bottom plan view thereof;

FIG. 8 is a perspective view of the folding-platform bicycle carrier in an alternate configuration;

FIG. 9 is a front elevational view thereof;

FIG. 10 is a rear elevational view thereof;

FIG. 11 is left side elevational view thereof;

FIG. 12 is a right side elevational view thereof;

FIG. 13 is a top plan view thereof; and,

FIG. 14 is a bottom plan view thereof.

The broken lines illustrate portions of the article that form no part of the claimed design.
